UNITED STATES PATENT OFFICE.

JOHN SANFORD SMALL, OF ELKHART, INDIANA.

FILE.

Application filed December 17, 1926. Serial No. 155,408.

This invention relates to a novel file of the class in which the cards are arranged in overlapping relationship in a frame or panel-like tray. The invention will be best understood by reference to the following description, when taken in connection with the accompanying drawings of one illustrative embodiment thereof, while its scope will be more particularly pointed out in the appended claims.

In the drawings:

Fig. 1 is an elevation of a portion of a file exemplifying the invention;

Fig. 2 is a sectional view on line 2—2 of Fig. 1, but with one of the cards upstanding, the better to illustrate the structure;

Fig. 3 is a sectional view on line 3—3 of Fig. 1, but showing some of the cards swung toward the front end of the tray and resting upon the card rest; and

Fig. 4 is a sectional view on an enlarged scale on line 4—4 of Fig. 1.

Referring to the drawings, and to the embodiment of the invention which is selected for exemplification, there is shown a paper file comprising a series of sheets or cards 5, herein having overlapping margins 6 to which identifying matter may be applied, thereby constituting an index for the file. Each sheet is associated with and supported by an appropriate support, such as a bar 7, which may be and herein is a flat, elongated strip of metal, which in turn is supported by a suitable support, in the present embodiment a panel-like tray comprising a body of sheet material such as sheet steel, presenting a web 8 and two upstanding walls 9, presenting outwardly directed flanges 10 and margins 11, parallel with the walls 9.

The panel or tray presents appropriate guides, such as channels 12, receiving the ends of the bars 7, the latter being parallel with, and edge to edge with, one another. Herein, the channels 12 are presented by sheet-metal strips 13 between the walls 9, and suitably secured in place as by spot-welding them to the web 8. Each strip is provided with an inwardly-directed flange 14, which overlies the adjacent ends of the bars. The bars are held in a somewhat elevated position,—that is to say, spaced from the web 8 of the tray by the provision of ribs 15, formed lengthwise of the strips 13. Making the flanges 14 and ribs 15 as parts of separate strips 13 possesses sev-

eral important advantages, among them being accuracy of spacing of the channels with respect to the width of the tray, accuracy in the depth of the channel from front to back, accuracy in the formation of the location of the ribs, and great strength, owing to the fact that the strips reinforce the web 8, as well as the walls 9.

Removal of a given bar from and its replacement in the channels may be, and herein is, conveniently accomplished by making the bars flexible and resilient, whereby they may be sprung or bowed to reduce their effective length to a distance less than the space between the edge of one flange 14 and the bottom of the channel 12 on the opposite side.

Each sheet is conveniently secured to its bar by two hinges, each comprising two hinge members 16 and 17, one secured to the bar and the other to the sheet, and a pintle 18, on which one hinge member turns relatively to the other. My present invention is in no way concerned with the details of these hinges.

The front end of the panel or tray presents a front wall 19, herein provided with a handle or knob 20, conveniently secured to the wall, as by a fastening means presenting a head 21 on the inner face of the wall. Between this wall and the nearest card-supporting bar is a card rest 22, herein conveniently formed of sheet-metal arranged in a sloping position, and having at its front end a depending flange 23, the lower edge of which rests upon the web 8. This flange is directed rearwardly to afford space for the head 21. This card rest is provided with lateral projections or tabs 24, received behind or beneath the flanges 14, and conveniently secured thereto to prevent displacement of the card rest longitudinally of the flanges, by providing the tabs with perforations 25 (see Fig. 4), which receive protuberances 26 on the flanges. These protuberances are conveniently formed by means of a prick-punch, or a center punch, after the tabs have been introduced beneath the flanges 14.

To afford access to the lateral edges of the cards when they are turned forward to rest upon the card-rest, (see Fig. 3), the card-rest has edges 27 extending lengthwise of the flanges 14 and spaced therefrom by a substantial distance, thereby enabling the edges of the cards to be fingered by the introduction

of the fingers between the edges of the card-
rest and the edges of the adjacent flanges.
This enables the cards to be handled rapidly.

Having thus described one embodiment of
the invention, but without limiting myself
thereto, what I claim and desire by Letters
Patent to secure is:

1. In a file, the combination of a frame comprising a body of sheet material presenting a web and two parallel walls outstanding from said web, two bodies of sheet material secured to said web between said walls and presenting flanges directed inwardly toward each other, and a card rest intermediate said walls and presenting lateral projections disposed between said flanges and said web, said flanges and said projections having interengaging means preventing displacement of said card rest lengthwise of said flanges.
2. In a file, the combination of a frame presenting a web, two flanges directed inwardly toward each other, and a card rest intermediate said flanges and presenting lateral projections disposed between said flanges and said web, said projections and said flanges

having interengaging means preventing displacement of said card rest lengthwise of said flanges.

3. In a file, the combination of a frame presenting a web, two flanges directed inwardly toward each other, and a card rest intermediate said flanges and presenting lateral projections disposed between said flanges and said web, said projections being provided with perforations and said flanges being provided with protuberances received in said perforations, respectively.

4. In a file, the combination of a frame presenting a web, two flanges directed inwardly toward each other, and a card rest intermediate said flanges and having edges extending lengthwise of said flanges and spaced a substantial distance therefrom to permit the edges of cards resting on said card rest to be fingered to enable the cards to be separated from one another.

In testimony whereof, I have signed my name to this specification.

JOHN SANFORD SMALL.
